UNITED STATES PATENT OFFICE.

FREDERICK H. MARTIN, OF AKRON, OHIO, ASSIGNOR TO THE B. F. GOODRICH COMPANY, OF NEW YORK, N. Y., A CORPORATION OF NEW YORK.

DESIGN FOR AN OVERSHOE.

Application filed March 26, 1926. Serial No. 17,058. Term of patent 14 years.

To all whom it may concern:

Be it known that I, FREDERICK H. MARTIN, a citizen of the United States, residing at Akron, in the county of Summit and State of Ohio, have invented a new, original, and ornamental Design for an Overshoe, of which the following is a specification, reference being had to the accompanying drawing, forming a part thereof.

Fig. 1 is a perspective view of an overshoe embodying my invention.

Fig. 2 is a different perspective view of the same.

I claim:

The ornamental design for an overshoe as shown.

FREDERICK H. MARTIN.
